CLAIM

The ornamental design for a gun sight as shown and described.

DESCRIPTION

FIG. 1 is a front view of a gun sight, showing our new design;

FIG. 2 is a back view thereof;

FIG. 3 is a left view thereof;

FIG. 4 is a right view thereof;

FIG. 5 is a top view thereof;

FIG. 6 is a bottom view thereof;

FIG. 7 is a front, left, top perspective view thereof;

FIG. 8 is a front, right, top perspective view thereof;

FIG. 9 is a back, right, top perspective view thereof; and,

FIG. 10 is a bottom perspective view thereof.

The broken lines in the drawings depict portions of the gun sight that form no part of the claimed design.

1 Claim, 10 Drawing Sheets
